UNITED STATES PATENT OFFICE.

HARRY W. JORDAN, OF SYRACUSE, NEW YORK, ASSIGNOR TO SEMET-SOLVAY COMPANY, OF SYRACUSE, NEW YORK, A CORPORATION OF PENNSYLVANIA.

METHOD OF PREPARING FUEL BRIQUETS.

No. 857,287.

Specification of Letters Patent.

Patented June 18, 1907.

Application filed August 6, 1906. Serial No. 329,514.

To all whom it may concern:

Be it known that I, HARRY W. JORDAN, a citizen of the United States, residing in the city of Syracuse, county of Onondaga, and State of New York, have invented a new and Improved Method of Preparing Fuel Briquets, of which the following is a specification.

Such briquets are usually made of fuel, such as coal, mixed with a combustible binder, such as coal tar pitch or asphaltum, which are formed into a plastic mass and compressed into briquets. In order to effect this, it is necessary that the binder shall be distributed as uniformly as possible through the mass of fuel to be briqueted, and it has been the practice heretofore to either grind the binder separately from the fuel to be briqueted, and afterward mix it therewith, or to grind the binder and the entire mass of fuel to be briqueted together, or to mix the binder with the fuel when the former is in a melted state.

My invention relates particularly to this part of the process of briquetting, and the object of my improvements is, to increase the solidity of the briquet, by securing a more uniform distribution of the binder throughout the entire mass of fuel, to the end of preventing crumbling of the briquets while burning and thus securing freer and more uniform combustion throughout the mass, and at the same time to reduce the cost of grinding.

To this end my invention consists in first grinding the binder, as pitch or asphaltum, together with less than the entire quantity of fuel, as coal, with which such quantity of the binder is adapted or intended to be used. The proportions of the binder and fuel used in this primary mixture may be widely varied, but I find in practice that by using one part of pitch with from three to four parts of coal, by weight, the best results are obtained. As the proportion of coal is increased above this, the cost of grinding will be increased, and as it is reduced below this, it will become more difficult to reduce the binder to the required degree of fineness. The mass may be

ground to any desired degree of fineness consistent with economy. In general terms, the more finely it is ground, the better it is adapted for the subsequent steps of the process. By grinding in this manner, the cost of grinding is materially reduced below that of grinding a quantity of the binder mixed with the entire quantity of fuel with which it is to be used, and at the same time it is possible to grind pitch of so soft a grade, or in so soft a state, that it cannot be ground by itself in any ordinary manner. The finely ground coal and pitch are then thoroughly mixed in any usual or convenient manner with coal of a coarser size, in such proportions as may be desired to make up the briquets. The particles of the coarse part of the mass, while considerably larger than those of the finely ground part, should not be so large but that the interstices between them will be readily and completely filled by the finely ground coal and binder, so that the mass will be solidly cemented together. In practice I find that the best results are obtained when the coarser part is of such size that the particles will pass through a ten mesh screen. After the mixing is completed, the mass is heated to soften the binder, and the briquets are compressed in any usual or convenient manner. In case other ingredients are used in the briquets, which require to be finely ground, they may be either ground separately or together with the coal and pitch mixture.

By means of my invention, I not only reduce the cost of grinding the materials of fuel briquets, but am able to produce a briquet which is more solid than heretofore, by reason of the more uniform distribution of the binder throughout the mass, and which has better burning qualities than those heretofore known, advantages which will be readily appreciated by those skilled in the art.

What I claim as new, and desire to secure by Letters Patent, is:

The method of preparing material to be briqueted, comprising coal, or other fuel material, or materials, or any combination thereof, and a binding material, which con-

sists in grinding together the binding material and a part of the coal or other material or materials to a fine state, and then mixing the finely ground mass with the remainder of 5 the coal or other material or materials in a coarser state, substantially as and for the purposes set forth.

In testimony whereof, I have hereunto subscribed my name, this second day of August, A. D., 1906.

HARRY W. JORDAN.
